Primary Examiner — Samantha Wood(74) *Attorney, Agent, or Firm* — Woodard, Emhardt, Henry, Reeves & Wagner, LLP(57) **CLAIM**

The ornamental design for a corner lavatory, as shown and described.

DESCRIPTION

FIG. 1 is a left perspective view of a corner lavatory, showing my new design;

FIG. 2 is a right perspective view thereof;

FIG. 3 is a front elevation view thereof;

FIG. 4 is a back elevation view thereof;

FIG. 5 is a right elevation view thereof;

FIG. 6 is a left elevation view thereof;

FIG. 7 is a top plan view thereof; and,

FIG. 8 is a bottom plan view thereof.

The broken lines are included for the purpose of illustrating portions of the article and form no part of the claimed design.

1 Claim, 5 Drawing Sheets(56)
